LOCK CONSTRUCTION

Ludwig J. Kalwo, Bronx, N. Y., assignor, by mesne assignments, to Keil Lock Co. Inc., Charlestown, N. H., a corporation of New Hampshire

Application February 2, 1945, Serial No. 575,922

4 Claims. (Cl. 292—169)

1

This invention relates to lock construction. One of the objects of this invention is to provide a simple, inexpensive, and practical lock construction in which turning of the key to withdraw the bolt brings about a releasable holding of the bolt in withdrawn position, thus to free the key hand to operate the door latch or knob. Another object is to provide a practical, reliable, and inexpensive mechanism for temporarily holding the bolt withdrawn in response to operating the key. Another object is to provide a strong, inexpensive, and durable mechanism for yieldingly holding withdrawn the bolt of a lock mechanism. Another object is to adapt, in an inexpensive but reliable manner, known types of lock constructions so that the bolt may be releasably held withdrawn in response to and under the control of the external member or members by which the position of the bolt is controlled. Another object is to facilitate, at low cost, the embodiment in known types of lock constructions, of simple, reliable, and efficient mechanism for releasably holding the bolt withdrawn and responsive to the actuation of the external bolt-controlling element or elements. Other objects are, in general, to provide an improved lock construction, and still other objects will be in part obvious or in part pointed out hereinafter.

The invention, accordingly, consists in the features of construction, combinations of elements, and arrangements of parts as will be exemplified in the structure to be hereinafter described and the scope of the application of which will be indicated in the following claims.

In the accompanying drawing, in which is shown illustratively one of various possible embodiments of my invention—

Fig. 1 is a central longitudinal sectional view through a lock construction showing the embodiment therein of the bolt holding means;

Fig. 2 is a fragmentary sectional view as seen along the line 2—2 of Fig. 1, certain parts being omitted; and

Fig. 3 is a fragmentary sectional view as seen along the line 3—3 of Fig. 1.

Similar reference characters refer to similar parts throughout the several views of the drawing.

Referring, first, to Fig. 1, I provide a lock casing 10 having a top wall 11, front and back end walls 12 and 13, respectively, and opposed side walls 14 and 15, the casing being adapted to be closed by a back plate 16 which is preferably in the form of a stamping of suitably heavy sheet metal and which is positioned in spaced rela-

2

tion from the front wall 11 by suitable lugs 18 in the internal side and end walls of the casing 10 and also by a substantially centrally positioned post 19 that projects from and is integrally formed with the front wall 11.

Projectable from a suitable opening in the end wall 12 is a bolt 20, illustratively shown as being a latch bolt, and it is extended inwardly of the casing with various parts of which, including the back plate 16, it coacts to be guided in its movement into or out of locking relation with respect to a suitable keeper (not shown).

Illustratively bolt 20 may be bifurcated, having two parallel arms that extend toward the right, terminating in vertical lugs 23 and 24 adapted to be engaged by the cam 25 that is to be operated internally of the door, as by a knob 26, rotatably mounted in the front wall 11, and by a cam 27 that is to be operated by the connecting bar 28 attached to the key-controlled key plug 29 rotatably mounted in a suitable bore of the lock cylinder or barrel 30, of any usual or suitable type key-controlled tumbler mechanism.

The bolt 20, where it is of the latch type, has a spring 32 to bias it outwardly of the casing 10, one end of the spring extending over a suitable tapered lug 33, projecting to the right from the head of the bolt, and the other end of the spring abutting against the post 19, the spring 32 being accommodated amply in the space between the arms 21 and 22 of the bolt 20; any suitable means may be employed to limit outward projection of the bolt 20 and, conveniently, that may be done by a cross-piece or cross-bar 34 that extends from one arm 21 to the other 22, being conveniently cast integrally therewith and being positioned so that it engages the post 19 at just the point where outward projection of the bolt 20 is to be limited. Suitable lugs projecting upwardly and downwardly from the bolt structure, as seen in Fig. 1, and including the end lugs 23 and 24, engage the top wall 11 and the back plate 16, or engage suitable guideways in the front wall 11, so that the bolt 20 is slideably guided for movement in withdrawing or projecting directions.

In accordance with certain features of my invention I provide, preferably as an integral part of the back plate 16, a rigid upstanding lug 36 positioned to coact with the arms 27^a and 27^b of the cam 27, and I provide a rotatable mounting of the cam 27 in the back plate 16 that gives the cam 27 a substantial extent of radial looseness or play, and this I may do by providing a hole 37 in the back plate 16 that is of substantially greater radius than the bearing portion of

the cam 27; thereby the cam 27 is physically shiftable relative to the back plate 16, for a purpose later described.

The cam 27 has a bearing portion, coacting with the hole 37, that may be of any suitable or desired form, but preferably, and solely by way of illustration, that portion and the general structure of the cam 27 and its assembly to the back plate 16 take the form disclosed in Patent No. 2,225,545, to which reference may be made for details involved. For present purposes it is sufficient to point out that, in such case, the cam 27—in the form, preferably, of a sheet metal stamping—has opposed arcuate parts 27^c and 27^d bent at right angles to its plane and terminating in outwardly extending flanges 27^e and 27^f; the hole 37 in back plate 16 has an extension 37^a which, in arcuate and peripheral extent, is slightly greater than that of either of the flange parts 27^e and 27^f, so that either of the latter can pass therethrough.

For assembly, therefore, one of the parts 27^e or 27^f, viewing Fig. 3, is snaked through the hole 37 so as to underlie the back plate 16; then, by suitable rotary movement of the cam 27, the other part 27^f or 27^e is brought into alignment with the cutout 37^a so that it may pass therethrough and upon continued rotary movement thus also brought to underlie the back plate 16. In that manner, according to the above-mentioned patent, the cam is easily assembled to or disassembled from the back plate.

Where such a cam structure is modified to gain the assembly advantages just noted, the radius of curvature of the opposed arcuate bearing portions 27^c and 27^d and the radius of curvature of the bearing portion of the hole 37 are purposely made different to give the above-mentioned play in a radial direction, and that play may be on the order of $\frac{1}{16}$ of an inch or so, and, in somewhat exaggerated form, that difference and that play are indicated in Fig. 3 of the drawing. Centrally located with respect to the arcuate bearing portions 27^c and 27^d is a rectangular hole 38 to receive the connecting bar 28 above mentioned, so that the cam 27 may be given rotary movement in either clockwise or counter-clockwise direction (Fig. 3), as may be needed, under the control of the tumbler block mechanism 29—30, and I have found that a substantial amount of play does not interfere with ease and appropriate actuation of the cam 27 by the key mechanism.

Accordingly, and as better appears from Fig. 3, rotary movement in either direction of the cam 27 causes withdrawing movement, to the right, of the bolt structure 20, either arm 27^a engaging the bolt lug 23 for that purpose or arm 27^b engaging the lug 24. Under the resultant load or strain imposed upon the rotating cam 27, including the load, caused by the spring 32, which is compressed during withdrawing movement, the cam 27 has its bearing portions 27^c and 27^d urged toward the left, the play or looseness of bearing fit being, therefore, such that a subsequent shifting bodily of the cam 27 toward the right may take place, as later explained.

The rigid upstanding lug 36 in the back plate and the cam 27 are shaped to coact upon completion of the rotary movement necessary to withdraw the bolt 20, and taking part in this coaction is also the spring 32. The rigid lug 36 stands up from the plane of the back plate 16 and is substantially V-shaped (see Fig. 3), with its apex pointing toward but spaced from the axis of the bearing hole 37. The front or left edge 27^e of

the cam 27, in the illustrated embodiment, is preferably arcuate and may be of the same radius throughout—a radius such that, during rotary movement of the cam 27, it just by-passes or clears the apex of the lug 36—but in that edge I provide notches 27^h and 27^k so positioned that one of them, depending upon the direction of rotation, is brought opposite the rigid lug 36 just about at the moment when the arm of the other notch has completed withdrawing movement of the bolt 20. Since only one of the arms 27^a or 27^b takes the reaction of the spring 32 as it is being compressed during bolt withdrawal, that portion of the rotary bearing surface or surfaces of the cam 27 that is along the radius of the cam arm that effects bolt withdrawal is, due also to the torque imposed by the turning of the connecting bar 28, brought into tangential bearing contact substantially along the just-mentioned radius, thus shifting the location of the radial play to a point diametrically opposite.

For example, if the cam 27 in Fig. 3 is rotated clockwise, it is cam arm 27^a that moves the bolt to the right by engaging the bolt lug 23, and, just about when the point of engagement of arm 27^a with lug 23 reaches a "two o'clock" position, at which position the notch 27^k is approaching juxtaposition to the lug 36, the bearing portion 27^c finds itself pressed against that portion of hole 37 closely adjacent to the cutout 37^a, while the bearing portion 27^d finds itself spaced from the opposite wall portion of the hole 37. The next slightly continued rotary movement of the cam 27 is now more of a bodily displacement of the entire cam 27, being mostly a pivotal swinging thereof in clockwise direction, with the point of engagement of arm 27^a and the lug 23 serving as a pivot for such displacement, thus moving the arm 27^b bodily to the left to engage the walls of the notch 27^k against the lug 36—which can be somewhat rounded over, as shown in Fig. 3—and in the course of such bodily displacement or pivoting movement of the cam 27, the play between the bearing part 27^d and the above-mentioned opposite portion of the wall of hole 37 is taken up, that play facilitating the bodily displacement just described.

The interengagement of notch 27^k and the lug 36 hold the cam 27 against further rotary movement which is halted by the operator of the key at that point, for he feels the distinct snap-action which results, and that relationship of the parts is maintained by the spring 32 which acts upon the cam through arm 27^a to hold it displaced leftwardly and, hence, to hold the notch 27^k and lug 36 in engagement. The bolt 20 thus is held in withdrawn position.

The key 39, through the action of the key plug 29 with the cam 27, by way of the connecting bar 28, is likewise held in rotated position corresponding to bolt-withdrawn condition and, hence, cannot be withdrawn from the key plug 29. The operator lets go of the key and, with the same hand, can then operate the door knob or door latch handle and thus open the door, even though the other hand is encumbered by bundles or the like, and, having entered, the operator again takes hold of the key 39 to turn it to its normal position where it can be withdrawn from the key plug; the initial application by the operator of even only a slight torque to turn the key back, disengages the displaceable cam 27 and its notch 27^k from the lug 36, aided by the energy stored in the compressed spring 32 which acts upon the cam to tend to turn it and, hence, also the key

plug and key, in the direction to project the bolt 20. The bolt 20 thus snaps out into projected position, the key plug rotates to its normal vertical position so that the key may be withdrawn, the operator withdraws the key.

I have found it advantageous, also, to appropriately shape the edge 27^a of the cam 27 to function as a cam edge in relation to the rigid lug 36, functioning as a fixed cam follower, so that the major central or middle portion of the edge 27^a to either side of a central horizontal axis, in Fig. 3, is arcuate and of a radius such that, by the action of spring 32, it rides along the lug 36 to maintain the play between the cam bearing portions and the hole 37 substantially minimum throughout a substantial portion of rotary movement of the cam from its starting position, whence the portions of the edge 27^a—just before either notch reaches the lug 36, indicated at 27^m—are of progressively increasing radius, thus to cam and bodily displace the cam 27 somewhat to the right, as viewed in Fig. 3, thus to shift the play to a region between the left portions of the bearing surfaces between the hole 37 and the cam 27 and thus to prepare the cam 27, under the tension of spring 32, to snap in the general direction to the left when permitted so to do by the notch in the cam riding into relationship with the lug 36. This action is, in general, similar to the above-described bodily pivotal movement of the cam into position to latch the bolt in withdrawn position. Return rotary movement under the control of the key snaps the parts out of latching position and permits the latch bolt to snap into projected position.

Where the back plate 16 is made of sheet metal, it is provided with an aperture through which may be passed a screw 41 to be threaded into a threaded hole in the post 19, thus to hold the plate 16 assembled to the casing, and, in constructing the rigid lug 36 above described, instead of punching a hole in the plate 16 for the passage of the screw 41, I strike up a tongue or ear of sheet metal to leave a slot 42 of suitable width to freely pass the screw 41 and then conform that tongue or ear of metal by a suitable operation into the V-shape (see Figs. 1 and 3) and to thereby form the above-described lug 36. The V-shape given to the lug gives it substantial strength and rigidity, and misalignment of the various parts is not affected by the length or width of the slot 42 in the back plate, since the latter carries not only the lug 36, but also the cam 27, and, hence, the relationship to achieve the engagements and coactions above described can thus be fixed and remains unaffected by the relationship between the slot 42 and the screw 41, the plate 16 being substantially snugly fitted with the side and end walls of the lock casing 10 itself.

Where it is desired that the bolt 20 be held in withdrawn position in response to actuation of the knob 26, the bearing portion 26^a of the knob and the wall of the hole 11^a in the casing wall 11 are given relative radii to give the desired looseness of fit or the desired play for bodily displacement of the cam 25, as will now be clear in view of the above description of the rotary mounting of the cam 27 and the back plate 16. Cam 25 is secured to the inner end of the shank of knob 26 in any suitable way, and it has two arms 25^a and 25^b with notches 25^h and 25^e and with a cam edge 25^j, substantially the same as the corresponding parts of the above-described cam 27, and these parts coact with the spring 32 and with a fixed lug 19^a which may be cast as an

extension of the post 19 or of the front wall 11 of the casing 10, and which may be given a V-shape, if desired, as indicated in Fig. 2.

These parts coact in a manner which will now be clear, in that the coactions can be the same as was above described in connection with Fig. 3, and, accordingly, the latch bolt 20 may be held withdrawn in response to rotary movement of the knob 26 in either direction, the play between the bearing surfaces (exaggerated in Fig. 2) shifting so as to interengage a notch of the cam with the lug 19^a under the coaction of the turning torque and the action of the spring 32 to catch and hold the cam 25 in a position where its corresponding arm holds the bolt 20 in withdrawn position. The application of a slight torque to the knob 26 in reverse direction effects a quick disengagement, the spring 32 snapping all of the parts to initial or normal position.

It will thus be seen that there has been provided in this invention a lock construction in which the various objects above noted, together with many thoroughly practical advantages, are successfully achieved. It will be seen that the mechanism is simple, and inexpensive to construct and assemble; that complications of mechanisms are avoided, and that simplicity and reliability of action are dependably achieved.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A lock construction comprising a casing having a bolt movable into or out of the casing and a spring biasing the bolt outwardly of the casing, a cam operable to move the bolt inwardly of the casing and against said spring whereby said spring reacts upon said cam, an abutment integrally formed with a wall of said casing and positioned adjacent said cam so that at least a portion of the latter, when said cam is actuated to withdraw the bolt, moves into operative relation to said abutment, said abutment and said portion of said cam having coacting interengageable parts comprising a spring finger on one and a notch on the other forming a detent whereby, upon engagement of said parts, said cam is held against movement, and means mounting said cam for movement and for guiding it during movement to bring said cam portion into operative relation to said abutment and providing sufficient looseness so that the reaction of said spring upon said cam effects bodily displacement of the cam to bring said interengageable parts into interengagement, said wall having the abutment integrally formed therewith being the casing back plate which has a portion of its metal cut and bent out of its plane to form said abutment and to thereby leave an aperture adjacent said abutment, and a screw extending through said aperture and in threaded engagement with a part of the casing to hold the back plate assembled thereto.
2. A lock construction comprising a casing having movably supported therein a bolt for projection outwardly of the casing and for withdrawal into the casing, a spring acting upon said bolt to bias it in one direction relative to the casing, a cam journaled loosely, axially and transversely within said casing and having operating connections with said bolt and having means oper-

able from the exterior of the casing for actuating the cam whereby said spring reacts upon said cam when the latter moves the bolt in opposition to the spring, an abutment integrally formed with a wall of the casing and inclined transversely away from said cam and positioned so that at least a part of said cam is movable adjacent and relative to the abutment, the cam and the abutment having coating portions capable of interengagement comprising a spring finger abutment on one and a notch on the other forming a detent and capable, when interengaged, to hold said cam against movement, and means whereby said spring effects shifting of said cam to bring said coating portions of the cam and abutment into interengagement.

3. A lock construction comprising a casing having opposed front and back walls, a bolt having means mounting it for movement outwardly or inwardly of the casing and into projected and withdrawn positions respectively, a spring operating upon said bolt to bias it in one direction of movement, a rotary cam loosely journaled axially and transversely having operating connections with said bolt and adapted to actuate the latter against the action of said spring, an inclined, outwardly directed abutment integrally formed with one of said walls, and loose, axially and transversely journaled means rotatably supporting said cam relative to one of said walls and providing a loose bearing therefor adapted to permit radial and transverse displacement of the cam, said cam and said abutment having interengageable holding parts comprising a notch on the cam and a spring finger on the abutment of which the cam part is brought into engagement with the other in response to radial displacement of the cam under the action of said spring.

4. A lock construction comprising a casing having a bolt movable into and out of the casing and a spring biasing the bolt outwardly of the cas-

ing, abutment portions, and cam members operable selectively from each side of the casing to move the bolt inwardly of the casing and against said spring biasing whereby said spring reacts upon said cam members so that at least a portion of the latter, when one of said cams is actuated to withdraw the bolt, moves into operable relationship to one of said abutment portions, said abutment portions and said cam members having co-acting, inter-engageable parts comprising a member on one and a notch on the other forming a detent whereby, upon engagement of said parts, said cam and the bolt are held against movement, and means mounting said cam members for movement and for guiding them during movement to bring said cam portions into operative relation to one of said abutment portions, and providing sufficient looseness so that the reaction of said spring biasing upon one of said cam members effects bodily displacement of the cam and abutment portions relative to each other to bring said inter-engageable parts into interengagement and hold said bolt in retracted position, at least one of said cam members being connected to a connecting bar rotated adjacent one end by a key controlled plug and at its other end extending into said cam in keying engagement and with radial play.
